UNITED STATES PATENT OFFICE

2,285,805

STARTER SWITCH

Charles Chirelstein, Newark, N. J.

Application May 15, 1941, Serial No. 393,611

1 Claim. (Cl. 200—113)

The invention here disclosed relates to starter switches of the type covered in Charles Chirelstein Patents 2,236,671, April 1, 1941, 2,241,240, May 6, 1941 and 2,242,902, May 20, 1941.

One of the important objects of the invention is to improve the electron emissive coating of the bimetallic element of the switch, particularly to assure a more extensive and more uniform coating of such element than attained heretofore.

Further and more or less related objects are to obtain quicker heating effects and hence more rapid operation of the switch.

Also, it is an object of the invention to provide a switch of the type mentioned, which will be stronger and better in a mechanical sense than those heretofore produced.

Further objects will appear and the various novel features of the invention are set forth in the following specification and broadly covered in the claim.

In the accompanying drawing forming part of the specification, a present embodiment of the invention is illustrated, but it is realized that the structure may be modified and changed in various ways, all within the true intent and scope of the invention as hereinafter defined and claimed.

Fig. 1 is a side elevation of one embodiment of the invention, the envelope or container being indicated in broken lines.

Fig. 2 is a showing of the parts as viewed at right angle in respect to Fig. 1.

Fig. 3 is a cross-sectional and plan view as on substantially the plane of line 3—3 of Fig. 1.

Fig. 4 is a cross-sectional detail as on line 4—4 of Fig. 2.

In the embodiment of the invention illustrated, the stem 5, which carries the bimetallic switch element 6, is bent at an angle at 7, off to one side of the press or stand 8, and the bimetallic strip is attached at its one end at 9, so as to hang in an inverted position, Fig. 2, at the side of the press.

The other stem 10, is bent at its upper end at 11, above and toward the upright portion of the first stem and to this angled portion is attached the plate or tab 12, carrying at the underside at 13, a material such as magnesium or barium magnesium.

With this location and relation of parts, the magnesium or barium magnesium is flashed directly down into the bight or loop in the bimetal, which in this cupped or cup forming relation catches and holds the flash to an extent sufficient to insure complete and effective coating of the

entire inner surface of the bimetal. The over-standing plate or tab 12, acts as a cover or shield confining the flash at the top and directing it downward, substantially or for the most part, into the confining loop of the bimetal.

Contact between the bimetal and the other element of the switch is provided on expansion of the bimetal by a rod or strip 14, projecting laterally from the free end of the bimetal into the plane of the upright portion of stem 10.

The envelope or container for the switch parts is indicated in a general way by broken lines 15, in Fig. 1, it being understood that after evacuation, this envelope is usually filled with a gas or combination of gases, such as neon, argon, krypton or helium.

In a present method of manufacture, the combination leading in and supporting conductors 5 and 10, are cut off substantially even and the first bent relatively close to the press to form a short stem with a relatively long arm 7, projecting to the rear or away from the press to support the bimetal off to one side of the press and the other bent at a point further from the end of the stem to form a longer stem, with a shorter arm 11, projecting over the end of the press, above and toward the first stem for supporting the emissive coating carrying plate over the loop of the bimetal. This plate and the bimetal are readily secured to these angularly projecting arms as by welding. So combined, the parts constitute a particularly compact arrangement, projecting only a slight distance beyond the press and therefore constituting a small unit of rugged design, well able to stand any shocks to which such a switch may be subjected. The small size, compact arrangement of the switch elements enables the use of a particularly small enclosing envelope, reducing the clean-up and exhausting requirements and the amount of gas or gases necessary to fill the envelope.

What is claimed is:

A starter switch, comprising an envelope, a support projecting into said envelope, conductive stems projecting beyond the end of said support into the envelope, one of said stems having an angularly bent end portion projecting laterally to one side of said support, a bowed U-shaped bimetallic switch element having one end attached to said laterally projecting end portion of said stem and supported thereby in laterally spaced relation to one side of said support and with the loop of the same located to the side of the support and inward of the end of the support, the opposite free end of said U-shaped bimetallic

switch element being disposed toward the other stem and having a contact portion movable in the expansion of said bimetallic element toward and into engagement with a portion of said stem and a plate mounted on said latter stem in position substantially at a right angle to the longitudinal extent of said U-shaped element and extending laterally to that side of the support where said bimetallic switch element is located, said plate extending across the gap between the sup-

ported and the free, contact ends of said bimetallic switch element and faced directly into the loop of said U-shaped bimetallic switch element and said facing portion of said plate having an electron emissive coating directed toward and into said closed loop of said U-shaped bimetallic switch element.
